UNITED STATES PATENT OFFICE.

WILLIAM H. HARRISON, OF NEW YORK, N. Y., ASSIGNOR TO HIMSELF, AND ISAAC D. THOMAS, OF BROOKLYN, NEW YORK.

AIRSHIP.

986,418.

Specification of Letters Patent.

Patented Mar. 7, 1911.

Application filed November 15, 1909. Serial No. 528,035.

To all whom it may concern:

Be it known that I, WILLIAM HENRY HARRISON, a citizen of the United States, residing in the borough of Brooklyn, in the city and State of New York, engineer, have invented a certain new and useful Improvement in Airships, of which the following is a specification.

I have discovered that the reaction of the 10 gaseous matter ejected in great volumes at high velocity from explosive engines can, by a proper construction and management, be made to lift and maintain in an elevated position for traveling, a light structure 15 adapted to carry the machinery, and one or more persons. I believe it can be applied to carry large structures.

My motive power is peculiar in that I 20 utilize the force of the explosion, after it has left the engine cylinder. The carburetor and chamber for retaining the mixed gas are both unusually large, as the success of my device depends upon its ability to explode large quantities of gaseous mixture in 25 rapid succession. The movement of the piston is only utilized to draw into the cylinder a sufficient quantity of the fresh gas, and to compress the gaseous mixture. I 30 make the diameter of my cylinder and piston large in relation to the length of the stroke, and make the exhaust port of liberal area and well up in the side of the cylinder, so that the piston travels but a short portion of the stroke before the exhaust occurs. 35 The explosion is barely completed when the exhaust port becomes wide open.

The following is a description of what I consider the best means of carrying out the invention.

40 The accompanying drawings form a part of this specification.

Figure 1 is an outline, the lower portion a side elevation, and the upper portion a vertical section. Fig. 2 is a plan view of 45 the lower portion, with an outline of the upper parts indicated in dotted lines.

Similar letters of reference indicate like parts in all the figures where they appear.

A is the base or body, a light broad vessel 50 adapted to stand upright on land and to promote such position when the machine alights in fairly smooth water. I propose to make all the parts of such size as will allow the carrying of passengers and freight, 55 but will for the present purpose describe

a construction adapted for the operator only. It is intended to serve made of any size in all the exigencies of this important and dangerous art. It is especially of advantage over the ordinary forms of air ships 60 in its capacity to rise from a state of rest and to sink vertically in alighting without requiring any horizontal path. It can stop in mid-air and even move rearward if any emergency shall require it. 65

B etc., are the cylinders of a set of explosive engines. The fuel, preferably gasoline, is supplied thereto, and exploded therein in the same manner and with the same effect as has been several years in common 70 use in automobile carriages, motor-boats and other large and small classes of motors, except that the exhaust is earlier. I have shown in outline the general style of the explosive engine, and will assume using 75 four cylinders. The sparking and other details are those in common use.

The rapidly succeeding exhausts are delivered into a single upright pipe L and ejected at a high velocity through a smoothly 80 finished nozzle L', and the strong current is received axially on a smooth point M' extending centrally downward in the interior of a conoidal canopy M carried uprightly on the body A, held by sufficient 85 braces M². The whole under surface of this widely spread approximately dome-shaped member, which I have termed a canopy, is smooth and as far as practicable, frictionless, and its form and that of the 90 point M' is curved to receive the current of gas and deflect it, first smoothly spreading the jet, next gradually changing the upward motion to a radial and at last to a conical descending motion with which later it is discharged at the base of the canopy, 95 and by its reaction lifts the whole.

O is a nearly corresponding light inner shell mounted within the canopy M, and making a tight engagement with the nozzle 100 L'. It is not absolutely essential to success that the position of these parts be exactly concentric, but I prefer they be so. The intent is to have the strong current of escaping gases fill the whole space between the canopy M and the shell O. 105

P P P on one side and Q Q Q on the opposite side of the body A, are smaller tubes smoothly bent, arranged to receive corresponding gas from the same or a different 110

source as the exhaust before described, and to lead such currents in a downward direction, and usually with an inclination backward. The arrangement insures that the 5 re-action of the gas issuing therefrom will always lift the structure with more or less force, and when the side pipes are inclined rearward, will contribute also to impelling the structure forward. The pipes are each 10 connected to the source of gas through the medium of an easily-turning joint R. The operator, by any suitable means as the lever S can turn one of the rods on each side. It may be found preferable to turn all the 15 rods on each side, and I show the three on each side connected by a rod P' or Q' to properly effect the end desired, which is to give the operator control by which he can stop the machine by turning the connected pipe or pipes a little forward, or can, by turning them strongly forward, cause the structure to move backward,—and also to steer by slight movements on one side or both sides to give the slight changes of direction required in maintaining a practically straight course for the structure. Of course it is easy by such means to turn the structure rapidly to large extent, by turning one set of pipes forward, and allowing 25 the other to continue in its previous position, inclining backward.

There are in addition to the ordinary rudder A' at the rear end, horizontal wings A² which may be fixed or may be movable 30 at will by ordinary connections, adapted to aid both in restraining undesired changes of inclination, and in making changes of inclination when desired to ascend or descend.

Modifications may be made without 35 parting from the principle or sacrificing the advantages of the invention. I can use a greater or less number of the side pipes P and Q. I can vary the proportions of the canopy M and shell O within wide limits so 40 long as the gas is ejected forcibly downward on different sides, so as to lift equally. Parts of the invention can be used without 45

the whole. I can dispense with the canopy and effect the lifting by the pipes P and Q alone. I can use other means to obtain the 50 explosive gaseous mixtures. It may be practicable and economical to work by expansion of other gases.

I claim as my invention:

1. In a flying machine, in combination 55 with means for supplying gas with high velocity, horizontally arranged planes to aid in supporting the structure by the inertia of the general atmosphere, an upright plane A' with provisions for turning it as a 60 rudder and a series of trumpet shaped reaction nozzles harnessed together on one side, all capable of being turned to stop or reverse, and another series of corresponding nozzles operable independently on the other 65 side acting in conjunction with the first series each controlled by an independent device S within easy reach of the operator so as to allow turning in a limited space.

2. In a flying machine, in combination 70 with means for supplying gas with high velocity, a reaction nozzle directed upward, a canopy above, presenting a substantially concave under face, and a point near its center directed toward the incoming stream, 75 the surfaces being smoothly curved, adapted to spread the current of gas and direct it downward on opposite sides.

3. In a flying machine, in combination 80 with means for supplying gas with high velocity, a reaction nozzle directed upward, a canopy above, presenting a substantially concave under face, and a point near its center directed toward the incoming stream, 85 the surfaces being smoothly curved, adapted to spread the current of gas and direct it downward on opposite sides, and a smaller shell of nearly the same form fixed below.

Signed at New York N. Y. this 30 day of October 1909.

WM. H. HARRISON.
